MATCH PACKET

Robert James Sheridan, Detroit, Mich.

Application June 27, 1939, Serial No. 281,423

2 Claims. (Cl. 206—29)

My invention relates to a new and useful improvement in a match packet in which a plurality of matches are secured at one of their ends to a base and in which the matches ordinarily are enclosed by a suitable cover. This type of match packet is well known, the cover being fastened at one end to the base and swingable in its open position for exposing the matches. On one face of the base, abrasive is carried on which the matches may be struck, and it is customary to swing the cover flap into covering position before striking the match. However, thoughtless and careless persons frequently strike the match while the entire packet of matches is exposed, with the result that not infrequently the entire packet of matches is lit with consequent danger and sometimes damage. Experience has also shown that when this packet type of match packet is carried in the pocket the cover flap becomes loose, leaving the packet of matches uncovered in the pocket.

It is an object of the present invention to provide a packet of matches of this type in which the danger and disadvantages referred to may be avoided.

It is another object of the present invention to provide a match packet of this class having a cover flap doubled upon itself and pivotally connected at its opposite ends to the base and so arranged and constructed that when the base is swung to position for fully exposing the abrasive on the base the matches will be enclosed by the covering.

It is another object of the present invention to provide a match packet of this class so arranged and constructed that the movement of the cover to covering position may be easily and quickly effected.

Another object of the invention is to provide a match packet of this class in which the likelihood of the covering member moving into uncovered position while the packet is in a person's pocket is reduced to a minimum.

Another object of the invention is a provision of a match affording a maximum space on which printed matter may be displayed.

Another object of the invention is the provision of a match packet of this class which will be simple in structure, economical of manufacture, durable, compact, easily operated, highly efficient in use, and of attractive appearance.

Other objects will appear hereinafter.

The invention consists in the combination and arrangement of parts and structure illustrated

and described in the specification, in the drawing of which,

Figure 1 is a side elevational view of the invention in closed position.

Fig. 2 is a similar view showing the invention open.

Fig. 3 is a similar view showing the invention partly open.

Fig. 4 is a sectional view taken on line 4—4 of Fig. 1.

In the invention I have illustrated a plurality of matches 12 fastened at one of their ends to a base 13, which is covered by a strip of material 14 doubled upon itself. This strip covers 15 the butt end of the matches. The remaining portion of the matches is covered by a cover 15 consisting of a strip of material doubled upon itself and placed over the cover 14 in clasping relation. A rivet or other suitable fastener 16 is projected through the base 13, the cover 14 and the cover 15 so that the base 13 and the cover 14 may be swung on the fastener 16 as a pivot relatively to the cover 15 so as to place the individual matches projected outwardly from the cover 15 and render them accessible for use. On the face of the cover 14 is a layer 17 of carborundum or other abrasive material on which the heads of the matches may be struck. When the block of matches is swung on the pivot into the position shown in Fig. 2, this layer of carborundum will be covered by the cover 15 and inaccessible for use. Consequently, in order to render the layer 17 of abrasive accessible to use, it is necessary that the block 30 of matches be swung on the pivot back toward their normally concealed position. Experience has shown that when a user swings the matches partially into their covered position, invariably he will swing the matches into their fully covered 35 position and in this way the likelihood of striking a match while the heads of other matches are exposed beyond the cover 15 is reduced to a minimum.

Thus, it is believed that the various advantages referred to are arrived at and the disadvantages are avoided.

I recognize that various modifications might be made in the specific embodiment of my invention without departing from the spirit of the invention and it is my desire to incorporate these modifications within the claims attached hereto.

What I claim as new is:

1. A match packet of the class described, comprising: a base portion; a plurality of indi-

vidual matches secured at one of their ends to and projecting outwardly from one edge of said base portion and each provided with a head at its opposite end; an end cover for said base portion embodying a strip of material doubled upon itself in enveloping relation to said base portion and extending at its end beyond the connection of said matches with said base portion and overlying a butt end portion of said matches and terminating short of the heads for preventing disarrangement of said matches; a layer of abrasive material on the face of said end cover and extending transversely thereof at the line of fold; an outer cover embodying a strip of material doubled upon itself in enveloping relation to said matches and faced oppositely to said end cover, the ends of said outer cover overlying said end cover and terminating at their edges adjacent the margin of said abrasive material for leaving said abrasive material exposed; and securing means projected through said covers and said base portion for securing said end cover on said base portion and pivotally connecting said base portion and said end cover to said outer cover.

2. A match packet of the class described, comprising: a base portion; a plurality of individual matches secured at one of their ends to and projecting outwardly from one edge of said base portion and having a head at the opposite ends; an end cover for said base portion overlying opposite sides of said base portion and extending at its ends beyond the connection of said matches with said base and terminating short of said heads for preventing disarrangement of said matches; a layer of abrasive material on the face of said end cover; an outer cover embodying a strip of material doubled upon itself in enveloping relation to said matches and faced toward said end cover, the ends of said outer cover overlying said end cover and terminating at their edges short of said abrasive material for leaving said abrasive material exposed; and securing means projecting through said covers and said base portion for securing said end cover on said base portion and pivotally connecting said base portion and said end cover to said outer cover.
